[57] **CLAIM**

The ornamental design for a bottle tray, as shown and described.

DESCRIPTION

FIG. 1 is a plan view of my new design for a bottle tray showing the under surface thereof;

FIG. 2 is a plan view similar to FIG. 1 showing the upper surface thereof;

FIG. 3 is a side view from the lower edge of FIG. 2; the side view from the upper edge of FIG. 2 being a mirror image of FIG. 3;

FIG. 4 is an end view from the right side of FIG. 2; the end view from the left side of FIG. 2 being a mirror image of FIG. 4;

FIG. 5 is a perspective view of my new design for a bottle tray showing the under surface thereof; and,

FIG. 6 is a perspective view of my new design for a bottle tray showing the upper surface thereof.
